(57)

CLAIM

The ornamental design for a shoe, as shown and described.

DESCRIPTION

Shoe

3.1 Perspective

3.2 Front

3.3 Back

3.4 Left

3.5 Right

3.6 Top; and

3.7 Bottom

The design contains a shoe, a shoe upper and shoe sole as shown in the Figures.

(Continued)

The broken lines show portions of the shoe that form no part of the claimed design.

1 Claim, 7 Drawing Sheets
